[57] CLAIM

The ornamental design for a combined helmet and light,
as shown and described.

DESCRIPTION

FIG. 1 is a side elevational view of a combined helmet
and light showing my new design, the opposite side
being a mirror image thereof;

FIG. 2 is a top plan view thereof.

FIG. 3 is a rear elevational view thereof.

FIG. 4 is a front elevational view thereof.

Fig. 1
